UNITED STATES PATENT OFFICE.

LOUIS S. HUGHES, OF CHICAGO, ILLINOIS.

METHOD FOR TREATING FERRUGINOUS WATERS.

1,248,329.

Specification of Letters Patent. Patented Nov. 27, 1917.

Application filed October 2, 1913. Serial No. 792,960.

To all whom it may concern:

Be it known that I, LOUIS S. HUGHES, a citizen of the United States, residing at Chicago, in the county of Cook and State of Illinois, have invented certain new and useful Improvements in Methods for Treating Ferruginous Waters, as set forth in the following specification.

My invention relates to the method of 10 treating mine water and more particularly to the treatment of acid ferruginous water of the type frequently obtained in the operation of coal mines. The invention has for its object broadly to purify these waters by 15 removing the acid and astringent ingredients therefrom and to recover from the mine water merchantable by-products. The constituents of this water, which are actively injurious to health and which must be removed 20 to prevent contamination of streams, ponds and the like, are free sulfuric acid and sulfates of iron and alumina.

While my invention is herein described in connection with mine water, it may, of 25 course, be practised effectively in the treating of water from other sources without departing from the spirit and scope thereof. The term "neutralization" used in describing my invention refers not only to the reactions with the free acid but also to reactions with the acid equivalents of the compounds present which are subject to decomposition by alkalis and which give an acid reaction, it being necessary in the treatment 30 of the water that these latter substances, as well as the free acid be neutralized. Because of the very large volume of the water to be treated and the large amount of dissolved salts carried thereby, the use of the ordinary 35 water softening chemicals such as caustic soda and soda ash is inhibited because of their cost.

A principal object of the invention is to provide a process which will purify the 45 mine water and the like and make possible the collection and treatment of merchantable by-products through the use of cheap material and with a provision of simple and inexpensive apparatus.

50 A further object of the invention is to provide a process of treating mine water and the like which may be carried on without waste and without appreciable diminution of the material provided for the pur- 55 pose.

A still further object of the invention is to

recover from the mine water various products which may be used in the purification of gas and for the production of a pigment.

Additional objects and advantages of the 60 invention will be apparent from the following description when considered in connection with the accompanying drawing, illustrating a preferred form of apparatus to be used in the practice of my present invention. 65

On the drawing,

Figure 1 is a vertical central section of an apparatus which may conveniently be used in carrying out the method embodying my invention, and

Fig. 2 is a top plan view of the same.

The mine water as it flows or is pumped from the mine is preferably first passed over a large quantity of a raw carbonate of an alkali earth, limestone being preferably employed, the pieces of limestone being of relatively large size to permit the mine water to pass over, between and around the pieces. During this passage over the limestone the neutralization of the mine water proceeds 70 through three stages: First, the free acid is neutralized; second, a suspended colloidal precipitate is formed which shows no tendency to settle, and third, when the neutralization is almost complete the precipitate 75 coagulates and settles rapidly. The effect on the limestone is minute and the amount dissolved negligibly small for apparently after the neutralization of the free acid itself is complete the limestone acts chiefly as a cat- 80 aglytic agent. The settling of the precipitate should be delayed until after the limestone is passed and to this end I increase the 85 velocity of the water over the limestone toward the end of its passage. This may be 90 done in any of a number of simple ways, as for instance the limestone may be deposited in the bottom of a number of long troughs 95 and the water led successively therethrough, the cross-sectional area of the troughs 100 through which the water last passes being materially less than the cross-sectional area of the troughs into which it is first admitted. Such an arrangement of troughs is shown 105 on the drawing. A pipe 3 leading from the mine opens into a wide trough 4 in which is disposed a quantity of finely broken limestone 5. The pipe 3 enters the trough near its top and the water being delivered from the pipe falls between the adjacent wall 6 110 and a baffle-plate 7 perforated at its bottom as at 8 to cause the water to pass about the

limestone from the bottom. From this trough the water is conveyed by a pipe 9 to a second trough 10 of less width than the trough 4 and containing pieces of limestone 5 coarser than those in the trough 4. The pipe 9 connects with each of the troughs 4 and 10 adjacent to their top edges. A baffle-plate 21 similar in all respects to the baffle-plate 7 is provided in the trough 10 and 10 causes the mine water to flow from the bottom of the trough through the limestone. From the trough 10 the mine water is conveyed to a third trough 11 by a pipe 12, this trough being of less width than the trough 15 10 and containing pieces of limestone 13 larger than those in the trough 10. A baffle-plate 14 similar to the baffle plates 7 and 21 and similarly placed causes the mine water to come in contact with the limestone near 20 the bottom of the trough. These troughs are placed at different levels, the first and widest one 6 being at the highest and the last and smallest one 11 being at the lowest level. Although three troughs are shown 25 on the drawing it will be readily appreciated that any number may be employed. The reduced sectional area causes an increased rate of flow per unit area and consequently delays the settling of the precipitate and delays also the incrustation of the 30 limestone materially, although, of course, the limestone will in time become coated and will need to be replaced or cleaned. A proper sizing of the stone and adjustment 35 of the rate of flow will render this replacement or cleaning only occasionally necessary.

After passing the limestone the mine water may, if thought desirable, be subjected to the action of some alkali such as 40 quick or slaked lime, the action of the limestone, however, as it has already neutralized the free acid and formed the precipitate to be deposited, requires that very little quick 45 or slaked lime be added. If it is desired to hasten the precipitate still more a natural alkaline water may be introduced or it may be used instead of the lime treatment just described. If conditions are such that the 50 mine water may be conducted through sufficient troughs containing limestone both the alkaline water and the lime will be found unnecessary.

After the water has been entirely or substantially entirely neutralized I cause it to 55 be violently agitated. This agitation can be easily accomplished by passing it down a steep incline on which are placed obstructions to cause splashing of the water. The 60 agitation causes the precipitate to coagulate and to be readily deposited when the velocity of the water is reduced. This agitation may be produced in a number of ways, the incline shown on the drawing consisting 65 of a trough 15 narrowing toward its outlet

and provided with a plurality of triangular blocks 16 secured in the bottom of the trough to cause the water to ripple and agitate as it passes thereover. The trough 15 in the present instance forms an outlet for the last 70 limestone-containing trough 11. The water and the precipitate are next led into suitable settling vats, preferably having tangential inlet openings, the inlet opening being of relatively small area so that the water will 75 flow in at a high velocity into the vat. The high rate of velocity at which the water is thus conducted carries the greater part of the precipitate, which at this point of the treatment is ready to rapidly settle, well in 80 toward the center of the vat. The precipitate drops to the bottom of the vat so rapidly that water may be conducted continuously therethrough, it only being necessary that the vat be sufficiently large to permit the 85 water to remain in substantially a quiet state for an instant.

A suitable form of vat is shown on the drawing. This consists of a metal tank 17 of frusto-conical shape, the bottom of the 90 vat 18 being smaller than its top. The trough 15 extends into this tangentially so that the water whirls somewhat about the center during the settling of the precipitate. The outlet 19 is relatively larger than the 95 inlet and the water flows out from the vat at low velocity.

The precipitate is removed from the vat, preferably by a suitable suction pump (not shown) through a pipe 20 extending nearly 100 to the bottom of the vat, and delivered into a filter press where it is squeezed into compact cakes driving out much of the free water. The remaining water may be driven out, if desired, by blowing compressed air 105 through the press after it is filled with the precipitate. Other means for collecting the precipitate may be employed, of course, and I do not wish to be limited to the use of any particular means for this purpose. The 110 pressed cake thus provided may be used in the purification of gas or it may be converted into paint pigment. If the cake is roasted at a low heat in a reverberatory furnace a Venetian red pigment of fine quality 115 is produced.

In connection with the foregoing it is to be understood that as the mine water passes through the successive bodies of the limestone its movement not only will be accelerated by reason of the decreasing cross-sectional area of each of the troughs, but as the broken pieces of the limestone in each trough are larger than those in the immediately preceding trough the interstices between the pieces of each body are relatively larger than the interstices between the pieces of the preceding body. This reduces the frictional impedance to the passage of the water and tends to increase the velocity of 130

its flow. Furthermore, in the passage of the water and the precipitate through the trough 15 the incidental agitation causes the particles of the precipitate, which up to this point are held in suspension, to impinge upon and adhere to each other, the mass of the adhered particles becoming sufficient under this coagulation to quickly settle when the water enters the vat. Thus the precipitate accumulates in the vat and may be removed readily therefrom in the manner previously described.

It will be apparent, therefore, that mine water treated in accordance with my present invention may be cheaply purified through the provision of simple and inexpensive apparatus and that a valuable product will be obtained which may be used for the purification of gas, the manufacture of a paint pigment and for other purposes. The process is susceptible of numerous modifications and its steps may be varied in many ways without departing from the spirit or scope of the invention or sacrificing any of its material advantages.

I claim:

1. The process of treating mine water which consists in first passing the mine water over relatively small pieces of broken limestone and subsequently over relatively larger pieces.

2. The process of treating mine water which consists in first passing the water over relatively small pieces of a broken carbonate and subsequently passing said water over relatively larger pieces at a higher velocity.

3. The process of treating mine water, which consists in first passing the same over

relatively small pieces of a raw alkali earth, and subsequently over relatively larger pieces thereof.

4. The process of treating mine water, which consists in first passing the same over relatively small pieces of a raw alkali earth, and subsequently passing said water over relatively larger pieces thereof at a higher velocity.

5. The process of treating ferruginous water, which consists in subjecting the same in successive stages to the action of separated bodies of an agent possessing alkaline characteristics, whereby to neutralize the free acid contained in the water and to produce a suspended precipitate, said bodies being arranged in relation to each other to offer decreased resistance to the passage of the suspended precipitate as the latter advances through the successive stages of treatment, and then coagulating the suspended precipitate to effect sedimentation thereof.

6. The process of treating ferruginous water, which consists in subjecting the same in successive stages to the action of separated bodies of an agent possessing alkaline characteristics, whereby to neutralize the free acid contained in the water and to produce a suspended precipitate, accelerating the velocity of flow of the water in its transit through the successive stages of treatment, whereby to hold the precipitate in suspension, and then coagulating the suspended precipitate to effect sedimentation.

LOUIS S. HUGHES.
